UNITED STATES PATENT OFFICE.

LOUIS C. HILLER, OF MERIDEN, CONNECTICUT, ASSIGNOR TO THE MERIDEN SILVER PLATE COMPANY, OF SAME PLACE.

DESIGN FOR A BANJO CLOCK-CASE.

SPECIFICATION forming part of Design No. 17,075, dated January 25, 1887.

Application filed December 4, 1886. Serial No. 220,749. Term of patent 7 years.

To all whom it may concern:

Be it known that I, LOUIS C. HILLER, a citizen of the United States, residing at Meriden, in the county of New Haven and State of Connecticut, have invented and produced a new and original Design for Banjo Clock-Cases; and I do declare the following to be a full, clear, and exact description of the same, reference being had to the accompanying drawing, forming a part thereof, which represents my novel design in elevation.

The design consists of a clock-case representing a banjo and bearing a dial.

1 denotes a representation of the drum of a banjo; 2, the staff; 3, the strings; 4, the keys; 5, the string-bracket; 6, bridges; 7, the tightening-clamps, and 8 the dial, which occupies a position at the center of the drum.

Having thus described my invention, I claim—

1. The design for a clock-case, consisting of a representation of a banjo provided with a dial, substantially as shown.
2. The design for a clock-case, consisting of a representation of the drum and staff of a banjo, 25 having a dial at the center of the drum, substantially as shown.
3. The design for a clock-case, consisting of a representation of the drum, staff, strings, keys, string-bracket, bridges, and tightening-clamps 30 of a banjo, substantially as shown.

In testimony whereof I affix my signature in presence of two witnesses.

LOUIS C. HILLER.
